(57) **CLAIM**

The ornamental design for an outdoor LED light, as shown and described.

DESCRIPTION

FIG. 1 is a bottom and one side perspective view of the outdoor LED light showing the new design;

FIG. 2 is a bottom plan view thereof;

FIG. 3 is a top plan view thereof;

FIG. 4 is an opposite side elevation view thereof;

FIG. 5 is a front elevation view thereof; and,

FIG. 6 is a rear elevation view thereof.

The broken lines shown on the drawings depict portions of the light that form no part of the claimed design.
